CLAIM

The ornamental design for a mobile concrete plant with silos, as shown and described.

DESCRIPTION

FIG. 1 is a right side elevational view of a mobile concrete plant with silos, showing my new design; the left side being a mirror image thereof;

FIG. 2 is a top plan view thereof;

FIG. 3 is a front elevational view thereof;

FIG. 4 is a rear elevational view thereof;

FIG. 5 is a right side elevational view thereof in the travel position; and,

FIG. 6 is a perspective view in the working position.

FIG. 1

FIG. 2

FIG. 4

FIG. 3
